GAS BLAST ELECTRIC CIRCUIT BREAKER

Henry Trencham, Ruislip, and Harold Ernest Cox, Dollis Hill, London, England, assignors to General Electric Company, a corporation of New York

Application June 19, 1940, Serial No. 341,392
In Great Britain June 27, 1939

5 Claims. (Cl. 200—148)

This invention relates to circuit breakers for use in alternating current electric power systems especially those wherein a fluid blast is used for the extinction of the arc.

It is known to provide for the insertion of a resistance in series with a portion of the arc formed during the opening operation of circuit breakers and that such a measure provides a means for dealing effectively with circuits having a high rate of rise of restriking voltage. This feature is of particular use on gas or air blast circuit breakers wherein the inherent ability to deal with circuits of high severity is not great. It has been proposed to effect the insertion of the resistance in circuit breakers of the fluid blast type using an extinguishing nozzle by providing an auxiliary electrode in the throat of the nozzle or immediately behind the throat, this electrode forming a contact to which one terminal of the resistance is connected, the other terminal being connected to one of the main contacts, but this arrangement involves undesirable constructional complications.

The object of the present invention is to provide means for introducing the resistance in a more convenient and effective manner.

According to the invention, the resistance is connected in shunt with the arc initially formed on opening the breaker under load by connecting it between the main fixed contact and an auxiliary contact insulated from the fixed contact and located so as to be engaged by the movable contact in its passage towards the fixed contact in moving to closed circuit position.

The accompanying drawings illustrate in section portions of a complete gas blast breaker sufficient to enable the nature of the invention to be readily understood; Fig. 1 showing one form of construction, Figs. 2 and 3 details of the construction shown in Fig. 1, and Figs. 4 and 5 modified arrangements.

In carrying out the invention, the main fixed contact is preferably of nozzle-shape formation, such as shown at 3 in Fig. 1, and is adapted to be engaged by a movable contact in the form of a rod or tube 1. The main fixed and movable contacts may, however, make butt engagement with one another. In one arrangement the gas blast is introduced between the contacts in such a manner (by providing inlet and exhaust openings on opposite sides of an insulating tube 4 in which the movable contact moves and which supports the fixed contact at one end) that the gas blast flows mainly across the arc formed between the contacts in a direction transverse

to the axis of the movable contact. The gas blast may be directed across the arc by means of an arc extinguishing structure generally indicated at 5 comprising a plurality of discs of insulating material stacked together and mounted in the insulating tube between the inlet and exhaust openings, and shaped to provide separate blast passages on either side of an arc splitter member incorporating the auxiliary contact at 11.

Referring more specifically to Fig. 1 of the drawings the main current is carried by means of an axially moving contact rod or tube 1, which is surrounded near its lower end by a garter type of sliding contact (not shown) and engaging at its upper end with a fixed contact 2 of similar type. The contact 2 is supported in and electrically connected to a nozzle shaped member 3. The arc extinguishing medium as for example compressed air, is introduced into a cylinder 4 of insulating material which surrounds the main contact rod, and supports at its upper end the member 3 and at an intermediate position an arc extinguishing nozzle structure 5, which is adapted to direct the gas blast transversely of the path of movement of contact 1 from an inlet conduit 6 to an exhaust passage 7. The nozzle structure is preferably built up from discs 8 of fibre, shown in plan in Fig. 2, separating members 9, and at least one splitter member 10 shown in plan view in Fig. 3. A metal contact 11 which may be in the form of a flat ring is carried by the splitter member 10 and is used as an electrode for connecting to one end of a resistance 12, the other end of which is connected to the main fixed contact.

In the circuit interrupting operation therefore, the first portion of the movement of the contact rod 1 disengages it from the main contact 2, introducing the resistance and at the same time allowing the gas or air blast to pass across the arcing space. Further movement disengages the contact rod from the electrode 11 carried by the splitter member whilst leaving the extinguishing blast in operation on both the main and resistance contacts.

The blast of extinguishing gas or air may be supplied as shown to the cylinder surrounding the contact rod at a point on its length opposite to or adjacent to the venting orifice, or may be introduced further down the same tube at a point adjacent to the surrounding garter type of contact. In a further variation the garter type contact at the lower end of the contact rod may be mounted clear of the pressure cylin-

der which is closed at the bottom by insulating means having only a hole through which the contact rod passes, thus providing that in the full open position, there is a clear isolating break in air between the contact rod and the fixed main contact carried in the pressure head.

In another arrangement shown by Fig. 4, the gas blast flows mainly along the path of the arc formed between the rod-like movable contact 1 and a nozzle-shape orifice forming part of the fixed contact structure 3 and carried in an insulating tube 4 in which the movable contact slides, the pressure gas being introduced through an inlet opening as at 6 located in the side of the tube. In this arrangement the auxiliary electrode 11 is arranged to make contact laterally with the movable contact by allowing it to project through the side of the tube to a point adjacent to the path of movement of the movable contact.

In the arrangement shown in Fig. 4, the gas blast is introduced through the inlet conduit 6 and flows mainly in the direction of the arc formed between the contacts and partly across the arc since the auxiliary electrode 11 is made hollow to allow some of the pressure gas to escape therethrough. The electrode 11 in this arrangement extends through the wall of the tube 4 to a position adjacent to the path of movement of the contact 1 so as to be engaged by that contact as it moves into engagement with contact 2. The electrode 11 is connected as in the arrangement of Fig. 1, to the contact 2 through the resistance 12. The inside end of electrode 11 may have a coating of insulation 13 to prevent the arc from wandering to its outer wall surface.

The operation of the circuit breaker in opening is as follows: In the closed position current passes from the lower garter type contact 14 into the contact rod and thence from the top fixed socket contact, the resistance passing no current. When the contact rod moves down out of engagement with the socket contact the main current arc is forced into the nozzle comprised in this contact and is extinguished leaving current flowing through the resistance element via the tubular electrode. Further movement of the contact rod draws it clear of the tubular electrode when this in turn acts as an extinguishing nozzle for the resistance current.

It may be provided that in the completely open position, the contact rod is withdrawn from the insulating pressure cylinder in order that a clear isolating gap may exist between the main terminals.

According to a further feature of the invention shown by Fig. 5, the movable contact 1 is made hollow and the gas blast is caused to flow both through the hollow movable contact and through an orifice in the fixed contact structure during the movement of the contact away from the fixed contact structure. The arc formed between the auxiliary electrode and the movable contact is then extinguished by the flow of pressure gas through the hollow contact. The movable contact may, in this case, be hollow throughout its length, but is preferably made hollow as shown only at the end adjacent to the fixed contact structure, being then provided with side orifices such as at 18 through the wall at a point away from the contacting end. The orifices are preferably located at a position such that they are initially covered by means associated with the insulating tube which supports the fixed contact structure and are only uncovered when the

movable contact has separated a predetermined distance from the fixed contact.

In the construction shown in Fig. 5, the movable contact 1 is made hollow at its upper end and engages the fixed contact 2 which is made with the nozzle-shaped part 3 forming an exhaust blast passage as in the above described arrangements. The insulating tube 4 is closed near its lower end by the barrier 14' having a central aperture sufficient to allow the movable contact to pass through it. The barrier 14' and the fixed contact structure 2 are sufficiently spaced as shown to form with the insulating tube 4 an interrupting chamber. In the open position of the breaker the movable contact completely withdraws from the interrupting chamber and tube 4 giving an air isolating break between the lower end of the tube 4 and the contact 1. The lower garter contact for the movable contact 1 is not shown.

In the circuit opening operation compressed gas is introduced through the inlet conduit 6 and flows through the annular space 16 between the tube 4 and the fixed nozzle-shaped part 3 into the interrupting chamber and as the contact 1 is lowered, flows upwardly through the nozzle-shaped opening at 3 for extinguishing the arc. The gas blast also flows from the interrupting chamber downwardly through the hollow contact 1 to exhaust through the side orifices 18 which are then uncovered by the barrier 14' owing to the movement of contact 1. As the contact 1 leaves the contact 2 the resistance 12 is connected in shunt with the initial arc, and as the contact 1 leaves the auxiliary electrode 11 the secondary arc formed between contact 1 and the electrode 11 is extinguished by the downward flow of gas through the hollow centre of contact 1. It will therefore be seen that the arc is acted upon by two oppositely directed gas blasts from the interrupting chamber, one portion of the arc adjacent to the fixed hollow contact 2 being subjected to the blast flowing upwardly into the exhaust blast passage at 3 and another portion of the arc being subjected to the blast flowing downwardly through the movable hollow contact 1. The main arc between the contacts 2 and 1 is thus acted upon by two oppositely directed gas blasts while in the interrupting chamber, and in case the circuit is still uncleared the lower portion of the arc then attaches to the auxiliary electrode 11 to insert the resistance 12 for facilitating final interruption by the blast through the hollow contact 1.

It should be understood that our invention is not limited to specific details of construction and arrangement thereof herein illustrated, and that changes and modifications may occur to one skilled in the art without departing from the spirit of our invention.

What we claim as new, and desire to secure by Letters Patent of the United States is:

1. A gas blast circuit breaker comprising a fixed hollow contact forming a blast passage, a movable contact co-operating with said fixed contact, a hollow tubular insulating member for supporting said fixed contact and guiding said movable contact into co-operating relation therewith, means for moving said movable contact into and out of engagement with said fixed contact, inlet and exhaust apertures in said tubular member for directing a blast of arc extinguishing gas across the path of movement of said movable contact and thereby across the arc formed be-

tween said movable and fixed contacts and into said blast passage as they separate under load, an auxiliary contact disposed adjacent to the path of movement of said movable contact and adapted to make contact therewith as said movable contact moves towards or away from said fixed contact, a resistance connected between said fixed and auxiliary contacts, and an arc extinguishing structure also forming a blast passage disposed adjacent to said auxiliary contact for directing an auxiliary gas blast thereacross.

2. A gas blast circuit breaker comprising a fixed hollow contact forming a blast passage, a movable hollow contact co-operating with said fixed contact, a hollow tubular insulating member for supporting said fixed contact and guiding said movable contact into co-operating relation therewith, means for moving said movable contact into and out of engagement with said fixed contact, an inlet aperture in said tubular member for introducing pressure gas thereinto, said gas flowing out of said tubular member through said fixed and movable contacts and through said blast passage when they are separated, an auxiliary contact disposed adjacent to the path of movement of said movable contact and adapted to make contact therewith as said movable contact moves towards or away from said fixed contact, and a resistance connected between said fixed and auxiliary contacts, said hollow movable contact forming a gas blast passage adjacent to said auxiliary contact for also directing a gas blast thereacross.

3. A gas blast circuit breaker comprising an interrupting chamber, relatively movable contact structure separable to form an arc gap in said chamber, said relatively movable contact structure forming gas exhaust passages leading in opposite directions from said chamber, means for directing an interrupting gas under pressure into said chamber, means for causing separation of said contact structure so that one portion of the arc within said chamber is subjected to a gas blast exhausting through one of said passages, and another portion of said arc is subjected to another gas blast exhausting in the opposite direction through the other of said passages, and fixed conducting means in said chamber to which the arc attaches from the movable contact struc-

ture, the arc at said conducting means being subjected to said last-named gas blast.

4. A gas blast circuit breaker comprising an interrupting chamber, relatively fixed and movable contacts separable to form an arc gap in said chamber, said relatively movable contacts forming gas exhaust passages leading in opposite directions from end walls of said chamber, means for directing an interrupting gas under pressure into said chamber, means for causing separation of said contacts so that the portion of the arc within said chamber at said fixed contact is subjected to a gas blast exhausting through the fixed contact passage, and the portion of the arc at said movable contact is subjected to another gas blast exhausting in the opposite direction through the movable contact passage, and fixed conducting means positioned in said chamber in sliding conducting engagement with said movable contact to which the arc attaches as said movable contact is being withdrawn from said chamber, the arc at said fixed conducting means being subjected to said last-named gas blast.
5. A gas blast circuit breaker comprising an interrupting chamber, relatively fixed and movable hollow contacts separable to form an arc gap in said chamber, said hollow contacts forming gas exhaust passages leading from opposite ends of said chamber, means for directing an interrupting gas under pressure into said chamber, means for causing separation of said contacts so that the arc at said fixed contact within said chamber is subjected to a gas blast exhausting upwardly through said fixed contact passage, and the arc at said movable contact is subjected to another gas blast exhausting downwardly in the opposite direction through the movable contact passage, and conducting structure positioned in said chamber in spaced relation to said fixed contact and in close electrical relation to said movable contact so that the arc attaches to said conducting structure from said movable contact as it is being withdrawn from said chamber whereby the arc gap between said fixed contact and conducting structure is of fixed length and is traversed by said oppositely directed blasts.
